UNITED STATES PATENT OFFICE.

JOSEPH B. BENGE, OF CHICAGO, ILLINOIS, ASSIGNOR TO D. B. SCULLY SYRUP COMPANY, OF CHICAGO, ILLINOIS, A CORPORATION OF ILLINOIS.

DESIGN FOR A SIRUP CAN.

Application filed July 24, 1928. Serial No. 27,570. Term of patent 14 years.

To all whom it may concern:

Be it known that I, JOSEPH B. BENGE, a citizen of the United States, residing at Chicago, in the county of Cook and State of Illinois, have invented a new, original, and ornamental Design for Sirup Cans, as shown in the accompanying drawing, and described in the following specification.

Figure 1 is a perspective view of one side

of the sirup can, showing my new design, and,

Figure 2 is a perspective view of the opposite side thereof.

I claim:

The ornamental design for a sirup can as shown.

JOSEPH B. BENGE.
